UNITED STATES PATENT OFFICE.

HERBERT W. CHENEY, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

RETARDED SWITCH.

1,344,199.

Specification of Letters Patent. Patented June 22, 1920.

Application filed August 5, 1918. Serial No. 249,578.

To all whom it may concern:

Be it known that I, HERBERT W. CHENEY, a citizen of the United States, residing at Milwaukee, in the county of Milwaukee and State of Wisconsin, have invented a certain new and useful Improvement in Retarded Switches, of which the following is a specification.

This invention relates to contact mechanisms and the actuating means therefor and may be applied in what are commonly known as overload relays, particularly in that type having a time element.

In contact mechanisms of the type above mentioned it is desirable that the circuit be broken or closed with considerable rapidity in order that the contact surfaces may not become roughened too greatly by arcing.

It is furthermore desirable that new surfaces be presented at the point of contact so that the arcing will not always take place at the same point.

One of the objects of the invention is to provide a contact mechanism in which a quick break is secured. Another object is to provide a contact mechanism in which the contacts are kept clean and new surfaces are periodically exposed. Still another object is to provide a combined wiping and rolling contact action.

In such retarded contact mechanisms as referred to above it is desirable that both the magnetic member of the relay and the retarding device be simply and conveniently adjustable and it is an object of this invention to provide a construction embodying these features.

Other objects will appear hereinafter as the description of the invention proceeds.

The various novel features of the invention will appear from this specification and the accompanying drawings which form a part thereof and disclose one embodiment of the invention, and all these novel features are intended to be particularly pointed out in the claims.

In the drawings, Figure 1 is an elevation of a retarded relay partly in section, embodying the various features of the invention.

Fig. 2 is an enlarged detail view of the valve mechanism of the dash pot, partly broken away, of the relay.

Fig. 3 is a section on the line III--III of Fig. 2 looking in the direction of the arrows. 55

Fig. 4 is a fragmentary view showing a different relative position of the contact members.

In Fig. 1 is shown a coil 1 provided for actuating the core 2 which is arranged to be drawn up within the coil when the latter is sufficiently energized. The core 2 is threaded on an actuating rod 3 which rod has an insulating spool 4 fastened in any suitable manner as by the pin 5 to the top end of said rod. The spool 4 is adapted to engage the contactor lever 6 in both directions of the movement and the contactor lever is provided with a notch or slot in the side thereof whereby the spool and the lever may be brought into coöperative relation.

The contactor lever 6 is pivoted at 7 in a double-armed bracket 8 fastened in any suitable manner to the insulating base 9. The contactor lever is provided with an arm 10 and a spring 11 acts upon this arm through a pin 12, the said spring, at its other end, being looped around a pin 13 in the bracket 8. The contactor lever is provided with a contact portion 14, here shown as of arcuate form. This contact is adapted to engage a roller-contact forming the relatively stationary contact of the contact mechanism. This roller-contact may be made of carbon or any other suitable material. The roller-contact is here shown as provided with a bushing 16 having a hole considerably larger than the positioning pin 17, mounted in the bracket 18. A spring 20 is provided for biasing the roller-contact toward the contact 14. A portion of the roller-contact and the bracket have been broken away in Fig. 4 to show clearly that the part 16 has a hole through which the pin 12 passes.

The coil 1 is lined with a tube 21 preferably of non-magnetic material, which tube is here shown as extending downwardly to form a support for the dash pot mechanism of which 23 is the lid of the dash pot 24. The dash pot is provided with a piston 25 slidable on a collar 26 on the piston rod 27. The piston is provided with any suitable number of holes 28 which, in the up-stroke of the mechanism as it is here embodied, are closed by means of the closure plate 29. 105 The plate 29 is fastened in any suitable

manner to the rod 27 as by spinning the lower end of the rod over the plate as is plain from the drawing.

The leak-valve mechanism of the dash pot includes an axial hole 30 in the piston rod 27, the lower end of the hole communicating with the space below the piston. Near the other end of the hole, that is, that portion above the piston, a transverse hole 31 in the piston rod communicating with the axial hole is provided. In order to provide for adjustment of the amount of fluid leaking through the hole 31, a tube 32 rotatably fitting over the piston rod is provided. The tube is provided with a slanting slot 33 here shown as cut half way through the tube. It is clear from Figs. 2 and 3 that as the tube 32 is rotated with respect to the piston rod, the hole 31 will be opened or closed more or less depending on the direction of rotation. By making the slot slanting, a longer range of adjustment is provided as is clear. The tube 32 may be set in any position by means of the set screw 34 which engages in the annular groove 35 in the piston rod. A portion of the walls of the tube 21 is cut away at 22 so that the tube 32 and core 2 may be manipulated.

The piston rod is fastened to the coupling 36 by means of the pin 37 and the coupling is in turn fastened to the actuating rod 33 as by threading thereto and by means of the pin 38. The hole in the piston rod for the pin 36 is made somewhat larger than the pin in order that the piston may adjust itself with respect to the actuating rod.

The operation of the device as a whole is as follows: If sufficient current passes through the coil 1 the core 2 will be attracted and pulled up, this motion being retarded by the action of the dash pot. After a time depending on the extent of opening of the hole 31, the lower collar of the spool 4 will engage the lower side of the contactor lever 6, moving the latter in a counter clock-wise direction until the spring 8 passes the dead center, whereupon said spring will snap the contact 14 to open position. Upon deenergization of the coil 1 the weight of the core 2 and the attached parts will rotate the contactor lever in a clock-wise direction so that contact 14 and roller contact 15 will reengage, the spring 8 assisting in this clock-wise rotation after the dead center is passed. The downward motion of the spool 4 and the attached parts is limited by the possible motion of the contact 14 with respect to the roller 15, which is in turn limited by the position of the pin 17 with respect to the bushing 16.

Returning more particularly to the operation of the contact mechanism itself, it will be noted that as the contact 14 moves in a counter clock-wise direction, and thus substantially tangentially with respect to the

roller-contact 15, the friction between the two contact surfaces will cause the roller 15 to rotate in a clock-wise direction. As the contact 14 recedes toward the left in a general direction with respect to the roller contact, the spring 20 gives the roller a motion of translation until the pin 17 and bushing 16 come into the position shown in Fig. 4, whereupon no further motion of translation toward the left is possible. In Fig. 4 the parts are shown in the position which the contact 4 assumes as it is about to leave the roller 15 or about to come into engagement therewith. Assuming now that contact 14 is moving in a clock-wise direction and coming into engagement with 15, it will be observed that conditions for the rotation of the contact of the roller 15 in a counter clock-wise direction are exceedingly unfavorable inasmuch as in order to rotate the roller 15 it is first necessary to force the spring 20 away from the pin 17 by means of the leverage action of the bushing, the pin 17 being used as a fulcrum. As a result of this, combined with the fact that, as stated, the pin 17 is being used as a fulcrum and there is therefore considerable friction at that point, there will be very little rotation of the roller 15 and the contact 14 will slip along the surface of the roller. It will be observed that the net result of the opening and closing of the switch comprising the contacts 14 and 15 is that the roller 15 will be rotated a substantially greater amount in the clock-wise direction than the counter clock-wise direction and thus new surfaces of contact will be periodically presented. Furthermore, a certain amount of wiping action between the contacts is present so that the surfaces are kept clean.

The structure of the contact mechanism itself, the presence of the snap action, the lost motion connection between the contactor and the actuating core, and the dash pot for retarding the upward motion of the core, all coact to produce the combined rolling and wiping contact. In this connection it will be noted that the upward or counter clock-wise movement of the contactor lever 6 is executed slowly by reason of the fact that the core 2 is retarded and that the snap action of the contactor lever to open position does not take place until after the roller 15 has been rotated to a considerable extent. On the other hand the relative motion between the contact 14 and the roller-contact 15, when the contact 14 is operated in a clock-wise direction, is comparatively rapid by reason of the fact that the snap action of the contactor lever 6 is then at its maximum. There is thus, during the contact making movement, a greater tendency for wiping action than there would otherwise be without the snap action and yet, as pointed out above, the retarded upward motion of the

contact 14 and the absence of snap action until after a predetermined amount of travel of the contact 14 in conjunction with the general structure of the contact mechanism,

5 causes a rolling or rotation of the contact 15.

It should be understood that it is not desired to limit the invention claimed to the exact details of construction herein shown and described, for obvious modifications

10 may occur to persons skilled in the art.

It is claimed and desired to secure by Letters Patent:

1. In combination, relatively movable co-acting contacts, one of which is rotatable, 15 supports for said contacts, and means including a lost motion connection between the rotatable contact and its support whereby when the contacts are moved relatively to each other the rotatable contact will be 20 rotated.

2. In combination, relatively movable co-acting contacts, a support for one of said contacts having a lost motion connection therewith, means for biasing said contacts 25 toward each other, said first mentioned contact being movable in a direction substantially tangential to said second named contact.

3. In combination, a movable contact, a 30 relatively stationary contact for coacting therewith, a support for said relatively stationary contact having a lost motion connection therewith, means for biasing said relatively stationary contact toward said 35 movable contact, said movable contact being movable in a direction substantially tangential to said relatively stationary contact.

4. In combination, a pivotally mounted 40 movable contact of arcuate form; a relatively stationary contact of substantially cylindrical form for coacting with said arcuate contact, an axial hole in said cylindrical contact, a positioning-pin smaller than said hole and passing therethrough,

45 and resilient means for biasing said cylindrical contact toward said arcuate contact.

5. In combination, a movable contact, a 50 relatively stationary rotatable contact co-acting therewith and means whereby when the movable contact is moved to one position the relatively stationary contact is rotated in one direction and when the movable contact is moved to another position the rela-

tively stationary contact is rotated a greater amount in the opposite direction, whereby 55 combined wiping and roller contact is secured.

6. In combination with a winding, a plunger for said winding, a tube within which said plunger is adapted to reciprocate, a retarding device attached to one end of said tube, an actuating rod for said retarding device extending into said tube, adjusting means for said retarding device also disposed in said tube, said tube having a 60 portion of its walls cut away whereby the plunger and adjusting means may be manipulated.

7. In combination, a winding, a movable magnetic member therefor, a movable contactor, a loosely mounted roller-contact for co-operating with said contactor, a lost-motion connection between said contactor and said magnetic member and means for retarding said magnetic member.

75 8. In combination, a winding, a movable magnetic member therefor, a movable contactor, a roller contact for co-operating with said contactor, a lost-motion connection between said contactor and said magnetic member, means for causing said contactor and said roller-contact to engage and disengage with a snap action and means for retarding said magnetic means.

9. In combination, a movable contact, a 80 relatively stationary contact, means whereby a motion of separation of said contacts causes a rolling motion of one of them and a motion of engagement causes a wiping action between them, and means for causing 85 a comparatively slow motion of said movable contact during the first part of the motion of separation, a rapid motion during the latter part of said motion, and a rapid motion during substantially all of the motion of engagement.

95 10. In combination, a movable contact, a relatively stationary contact, means whereby a motion of separation of said contacts causes a rolling action of one of them and a motion of engagement causes a wiping action between them.

In testimony whereof, the signature of the inventor is affixed hereto.

HERBERT W. CHENEY.
